United States Patent Office.

WILLIAM H. GRISCOM, OF SALEM, NEW JERSEY.

Letters Patent No. 87,842, dated March 16, 1869.

IMPROVEMENT IN GATE.

The Schedule referred to in these Letters Patent and making part of the same.

To all whom it may concern:

Be it known that I, WILLIAM H. GRISCOM, of Salem, in the county of Salem, and State of New Jersey, have invented a new and useful Improvement in Farm-Gates; and I do hereby declare that the following is a full and exact description thereof, reference being had to the accompanying drawings, and to the letters of reference marked thereon.

In the accompanying drawings—

Figure 1 is a side view of my invention or improvement in farm-gates.

Figure 2 is a top view of the same.

The object of my invention is to make a simple and very cheap farm-gate, that a farmer can make without any iron-work or other expensive parts.

My invention consists of a panel of rails, with posts and slides, so arranged that the bottom of the gate will always rest on at least two of the slides, and be held between two of the posts, so that the panel cannot be moved by the wind, and will not sag or require any braces whatever.

In the construction of my improved gate, the panel of rails may be put together in the simplest manner, as represented at F, fig. 1, the parts being only nailed together.

On each side of the gateway I set two posts, in the usual manner, with cap at top, to prevent the post from swaying with the wind.

At the foot of the posts I set slides H, one of which

is shown in dotted lines, for the gate to rest and slide upon.

Another slide is placed near the middle of the gate, between the posts, and a fourth slide, or rest, is set at E, to support and guide the gate when moved nearly open.

By sliding the gate to the left, it may be swung around, as shown in red lines in fig. 2.

A gate thus made is very cheap, being simply nailed together, and no braces being required. No hinges, rollers, or other expensive device is employed; therefore any farmer can make and hang the gate.

I prefer to use an oak bottom-rail, and also to make the slides of oak, so the gate may slide easily, the wood becoming smooth by wear between the bottom-rail and slides.

I do not broadly claim a sliding gate, but confine my claims to the above-described improvements.

Thus, having described my invention,

I claim the panel or gate F, when supported by and moved upon the simple slides, or rests H and E, substantially as set forth.

I also claim a gate which, upon sliding to one side, always rests upon slides, and when moved to the other side may be balanced and swung round, as shown in dotted lines in fig. 2.
